FIG. 1

FIG. 2

FIG. 3

FIG. 4

FIG. 5

FIGURE 1 is a front perspective view of a golf range finder showing my new design;

FIGURE 2 is a front elevation thereof, showing the same in closed position;

FIGURE 3 is a rear elevation showing the same in open position;

FIGURE 4 is a side elevation showing the range finder in the position of FIGURE 3; and

FIGURE 5 is a bottom view.

The dominant features of my design reside in the portions shown in full lines.

My design comprises a sliding scale golf range finder surmounted by a substantially flat representation of the upper half of a golf ball, which scale penetrates a matching half golf ball when closed, all as shown.

I claim:

The ornamental design for a golf range finder, substantially as shown and described.
